UNITED STATES PATENT OFFICE.

GEORGE M. HULL, OF DENVER, MISSOURI.

WAGON-BODY.

SPECIFICATION forming part of Letters Patent No. 276,821, dated May 1, 1883.

Application filed January 11, 1883. (Model.)

To all whom it may concern:

Be it known that I, GEORGE M. HULL, of Denver, in the county of Worth, and in the State of Missouri, have invented certain new and useful Improvements in Wagons; and I do hereby declare that the following is a full, clear, and exact description thereof, reference being had to the accompanying drawings, and to the letters of reference marked thereon, making a part of this specification.

This invention relates to certain improvements in the construction of wagons and other vehicles; and it has for its objects to provide certain improvements in building up the body upon the truck, whereby it may be readily put up and taken down, as more fully hereinafter specified. These objects I attain by the means illustrated in the accompanying drawings, in which—

20 Figure 1 represents a perspective view of a wagon-body showing my invention; Fig. 2, a transverse sectional view of a wagon-body, taken on the line xx of Fig. 1; and Fig. 3, a perspective view showing a detached portion of 25 one of the end-boards, showing the means by which it is secured to the body of the wagon.

The letter A indicates the bottom of the wagon, which is constructed preferably of a series of parallel boards, which rest upon trans- 30 verse cleats B, which are provided at their extremities with metallic extensions D, having hooks E, for the purpose hereinafter described.

The letter F indicates the lower side-boards of the wagon-body, which are provided with 35 metallic standards G, which are bent outwardly at their lower ends, and which are adapted to be engaged by the hooked ends of the extensions at the extremities of the trans-verse cleats which support the bottom.

40 At the ends of the bottom of the wagon are secured in any suitable manner the metallic bars H, which have loops or eyes I at their ends, as indicated.

The letters K K' indicate the end-boards, 45 which are provided with metallic bars L, which are secured in any convenient manner. The said bars are bent outwardly at their lower ends, so as to engage the hooked ends or eyes of the bars H, as indicated. The said end- 50 boards at their edges are provided with recessed attachments L', which are secured in

any convenient manner, and which are adapted to set over the edges of the vertical sides of the wagon-body and assist in holding the parts together. The said attachments are provided on the outside with bent links M, which are adapted to connect with the staples N, secured to the sides of the wagon, so as to hold the end-boards to their places.

55 At the tail of the wagon-body the sides have loosely attached to them the metallic segmental plates P by means of the bolts R, passing through curved slots S in said plates. The plates are provided at their vertical edges with sockets T, and the attachments L' at the edges of the tail-board with intermeshing sockets U, through which may be passed the bolts V, which hold the tail-board to the segmental plates before mentioned, so as to permit said tail-board to be dropped at an angle 60 and permit loose grain to be conveniently shoveled out.

65 The wagon-body is provided with upper side extensions, W, which have standards X secured to it, which are adapted to set in staples Y, secured to the lower side parts of the wagon. The ends of said extensions set in the recesses in the attachments at the edges of the end-boards, so as to make the body of the wagon strong and compact when the parts are 70 in place.

75 It will be seen that as thus constructed the parts of the wagon-body may be set up between the standards of the truck and taken down and stored away with but little inconvenience, as the parts are all detachable, and when taken down the bottom may be used to cover and protect the other parts when put up for storage.

Having thus described my invention, what I 80 claim, and desire to secure by Letters Patent, is—

1. The combination, in a wagon-body, of the bottom A, provided with suitable eyes at the ends and sides, the end pieces and side pieces 85 provided with vertical standards adapted to engage said eyes, the vertically-recessed sections, L', secured to the end pieces and forming seats for the side pieces, and the hooks and eyes by which the side and end pieces are 90 held together, substantially as specified.

2. The combination, with the side pieces, ar-

ranged and supported upon the bottom, as de-
scribed, of the vertically-recessed sections se-
cured to the tail-board, and the slotted seg-
ments connected to said tail-board by means
5 of interlocking hinge-joints and suitable pin-
tles, substantially as specified.

In testimony whereof I affix my signature, in

presence of two witnesses, this 21st day of De-
cember, 1882.

GEORGE MARTIN HULL.
